UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed July 5, 1924. Serial No. 724,186.

My invention relates to typewriting or like machines, and more particularly to means for rapidly jumping the carriage to bring different columnar fields successively 5 to the printing point.

The main object of my invention is to provide a comparatively simple, yet highly efficient, means of the character specified, and in which the jumping of the carriage 10 from one column to the next is brought about, in the main, automatically and there is no necessity of detracting from the written work produced by occupying the time and burdening the mind of the operator with 15 the actuation of a selected one of a series of keys each time the carriage is to be jumped from one column to the next.

To the above and other ends which will hereinafter appear, my invention consists in 20 the features of construction, arrangements of parts and combinations of devices set forth in the following description and particularly pointed out in the appended claims.

In the accompanying drawings wherein 25 like characters indicate corresponding parts in the different views,

Figure 1 is a fragmentary vertical fore-and-aft sectional view of the rear portion of a Number 12 typewriting machine embodying my invention.

Figure 2 is a fragmentary front elevation of the upper portion of the same.

Figure 3 is a fragmentary detail front view of the margin stops and associated 35 parts, illustrating a different relative disposition thereof from that shown in Figure 2.

Figures 4 and 5 are enlarged detail fragmentary sectional views of the backing pawl and ratchet, showing the different relationships of the parts thereof to accord with the 40 positions of the traveling margin stop as shown in Figs. 2 and 3 respectively.

Figure 6 is a detail fragmentary top plan view of the feed racks and other parts associated therewith.

Figures 7 and 8 are views of the same as seen and looking towards the right-hand end of the carriage; Figure 7 showing the ordinary feed rack engaging the feed pinion, and Figure 8 showing said feed rack locked 50 out of engagement with the pinion for control of the carriage by the tabulating rack.

Figures 9, 10, 11, 12 and 13 are detail frag-

mentary front views showing the feed pinion co-operating with different sections of the 55 compound tabulating rack.

Figure 14 is a detail fragmentary front view showing the tabulating rack engaging the feed pinion, and the ordinary rack maintained elevated out of engagement with the 60 feed pinion.

Figure 15 is a detail fragmentary front view of one of the rack sections and the feed pinion, showing the relation of the parts when the carriage is forced to the 65 right one letter space beyond its normal position at the beginning of a line.

Figure 16 is an enlarged detail fragmentary front view, showing another form of pinion co-acting with a section of the tabulator rack.

The machine of the present invention attains certain of the same general objects as the construction disclosed in my Patent No. 1,473,920 dated Nov. 13, 1923, and is intended 75 to improve certain features of said prior machine.

I have shown my invention in the present instance embodied in a No. 12 Remington machine, only so much of said machine being 80 shown as is necessary to arrive at an understanding of my invention in its inclusion therein. It should be understood, however, that the invention is not restricted to embodiment in this machine but may be used 85 in various styles of typewriting or like machines.

The machine as a whole may be understood to be the same as the No. 12 Remington machine with the usual tabulator mechanism omitted and certain changes made 90 therein, to be hereinafter indicated.

In the present instance the machine has been especially constructed and designed to write within columns of given character and spacing of a special blank form known as a toll service charge slip used by telephone companies, although obviously the invention is not restricted to such use, and the machine may be modified to accord with any 100 given character of blank that may be employed.

The usual spring driven carriage comprises a rectangular truck, and a platen frame in which is mounted a cylindrical platen 1. 105 The truck comprises a front cross bar 2, a

rear cross bar 3, and end bars 4. The rear cross bar 3 is grooved to receive crossed rollers 5, which likewise are received in a fixed guide rail 6. The front cross bar of the carriage is supported in a like manner to guide the carriage in its movements from side to side of the machine over the top plate 7. The platen frame comprises end bars 8 united by cross bars 9, 10, and 11, the platen frame being connected by links 12 and 13 to the truck. These links ordinarily enable the platen frame and the platen carried thereby to receive a case shifting movement. In the present instance, however, the usual screw stops 14, one of which is shown in part in dotted lines in Fig. 1, are threaded down to prevent a shift of the platen, as fully pointed out in my co-pending application, Sr. No. 610,058, filed Dec. 30, 1922, relating to the line spacing mechanism intended for use in this same machine.

A paper table 15 may be mounted in any suitable manner on the carriage. In the present instance the table is mounted in substantially the same manner as in the No. 12 Remington machine. Thus, blocks 16 are secured by screws 17 to the cross bar 9. A metal strip 18 is secured to each block 16 and is provided with an inwardly projecting pivot 19. Each pivot is received within a pivot bearing 20 of a strip 21 secured to the back of the paper table and provided with a resilient arm 22 adapted to engage the upper end of the companion strip 18 to latch the paper table against pivotal movement on its support. Two flanges or side edge gages 23 project forwardly from plate-like supporting members 23 secured to the front face of the paper table. These gages with the supporting members constitute a chute into which a work sheet 24 may be readily introduced and guided accurately to the throat between the platen 1 and the paper apron 25 at the introductory side of the platen. To further aid in the proper and rapid introduction of a blank into the machine, I have provided a deflector plate 26 mounted at its upper end on a pivot rod 27 supported at its ends in bearing openings in the guides 23. The deflector 26 is fixed to turn with its supporting or pivot rod 27, and extends downwardly and rearwardly therefrom and is supported at its lower edge against the rear side of the platen; the deflector being held at its bottom edge snugly against the platen by gravity. This deflector plate forms a fourth side of the chute and further aids in directing a rapidly introduced work sheet into the machine and to the usual feed rollers, not shown. The chute as a whole may be adjusted longitudinally of the platen by loosening the screws 17 and sliding the blocks 16 together with the parts mounted thereon along the supporting rod 9.

The carriage which is spring driven in the usual manner is controlled in its feed movement by the following means:

The feed pinion 28 is controlled by its escapement devices in the same manner as in the No. 12 Remington machine at each actuation of a printing key or the space key. However, I prefer to make the holding dog 29 of the escapement with a flat working face instead of a beveled working face, for reasons which will hereinafter appear. The feed pinion 28 is longer than that ordinarily employed but otherwise may be of the usual construction. This pinion is operatively connected with the escapement wheel 30 by the usual spring pressed pawl 31 and ratchet wheel 32 (Fig. 4), so that the escapement wheel and pinion turn together in one direction but the pinion is free to turn independently of the escapement wheel when turning in the opposite direction, as when the carriage is moving to the right. A depression of a printing key (not shown) is effective to actuate the usual type bar actuated universal bar, and through arms 33 (Fig. 1) connected therewith, transmit motion to a rock shaft 34, which in turn rocks an arm 35 thereon rearwardly. This movement is transmitted through a link 36 to a dog rocker 37 by which the holding dog 29 and a stepping dog 38 are carried; causing the stepping dog to be disengaged and the holding dog to be engaged with a tooth of the escapement wheel. Releasing the depressed key enables the dog rocker to return to normal position, when the carriage ordinarily advances one letter space. The ordinary space key of the machine, and of which each of the arms 39 may be regarded as a part, is connected through said arms to a rock shaft 40 mounted at its ends on the base 41 of the machine. A rocking of the shaft by the space key is effective, through the usual train of connections, to actuate the dog rocker. Thus, an arm 42 secured to the rock shaft carries an adjustable member 43 by which connection is made with a lever 44 pivoted at 45, and the upper arm 46 of which stands in front of a lug 36^a on the link 36. The arm 46 moves rearwardly on the depression of the space key and moves the link 36 rearwardly to move the dog rocker, the parts returning to normal position when the space key is released. The escapement mechanism as thus far described, with the exceptions hereinbefore pointed out, may be of the usual construction employed in the No. 12 Remington machine. As pointed out above, the feed pinion 28 is longer than that ordinarily employed. This is in order that it may co-act with two feed racks. One rack 47, corresponds substantially to the regular feed rack employed in the No. 12 Remington machine. The other rack, designated as a whole by

the reference numeral 48, is a specially constructed compound or multiple tabulator rack comprising a plurality of sections, each movable independently of the others 5 into and out of effective position, or into and out of engagement with the feed pinion, for bringing out tabulating movements of the carriage in accordance with my invention, as will presently more clearly appear. 10 What may be termed the ordinary feed rack 47, has regular spaced teeth 47^a (Fig. 14) extending continuously throughout the effective length thereof, and this rack is secured by screws 49 to upwardly bent ends 15 of two supports 50. The forward ends of these supports are formed with bearings 51 that receive and turn on a supporting rod 52 that extends throughout a considerable portion of the length of the carriage. This 20 supporting rod is received at its reduced ends in bearing openings in brackets 53 secured to the rear cross bar 3 of the carriage by screws 54. The feed rack 47 is thus pivotally supported to turn on the rod 52 into and out of engagement with the feed 25 pinion 28. A cross bar 55 is rigidly secured at its ends by screws 56 to upwardly and rearwardly extending arms 57 on the brackets 53. This bar is bored transversely 30 at intervals throughout the length thereof to form cylindrical openings or pockets 58, the bottom walls of the openings being uppermost as shown in Fig. 1. Seated within each of these pockets is a coiled expansion 35 spring 59. The lower end of each expansion spring bears in a counter-sunk opening 60 in the associated pivoted supporting arm, whether said arm be one of the arms 50 for the ordinary feed rack 47 or the corresponding arm for a rack section of the 40 tabulator rack to be hereinafter described. In this manner spring pressure is exerted downwardly on the arms 50 to hold the teeth of the rack 47 in engagement with the teeth of the feed pinion. In order to limit downward movement of the arms 50 (or the corresponding arms of the tabulator rack sections) I thread a screw stop 61 through tapped openings in each of said arms. The 45 lower end of each screw co-acts with the rear cross bar 3 of the carriage, or the cover plate 62 secured thereto, in order to limit the downward movement of the arm which carries said screw. A lock nut 63 co-acts 50 with each screw 61 to hold it in its adjusted position.

The ends of the rack 47 have forwardly extending lips 64 (see Figs. 6, 7 and 8) secured thereto and beneath these lips extend the rear ends of release levers 65. These levers are of the usual construction except that one is provided with an outwardly extending lug 66, for purposes which will hereinafter appear. Each lever 55 is pivoted to the carriage at 67, and is pro-

vided with a key 68 at its forward end. The stem of a headed shouldered screw 69 passes through an opening 70 in each release lever. On the screw 69 at the right-hand end of the carriage is pivoted an actuating 70 and locking lever 71 provided with a key or finger piece 72, a camming portion or edge 73, and a comparatively blunt end 74. When the lever 71 is in the position shown in Figure 7, the feed rack 47 normally engages the feed pinion and the machine will function as an ordinary correspondence machine, affording a letter space feed at each actuation of a printing key on the space key. 75 When, however, the locking lever 71 is 80 turned to the Figure 8 position, this results in the co-operation of the camming edge 73 of said lever with the lug 66 to shift the right-hand release lever 65 and lock it in the Figure 8' position, with the rack 47 held 85 out of engagement with the feed pinion 28. At this time, the blunt end 74 of the locking lever co-acts with the lug 66, as shown in Fig. 8, to retain the locking lever 71 in its 90 shifted position, indicated in this view. 95 This leaves the carriage in the control of the tabulator rack to function automatically and under the control of the space key, as will now be described.

Referring more particularly to Figures 1 95 and 6 to 15, it will be seen that the compound or multiple tabulating rack 48 is made up of, or comprises, in the present instance, five members or sections, 75, 76, 77, 78 and 79, although the number of such sections may be varied depending on the character of tabulating to be produced. These 100 rack sections are preferably, though not necessarily, aligned when in the normal position, as shown. Each of the sections is fixed, 105 by one or more screws 80, to and is supported on an arm 81 substantially like the arms 50, and like one another except that they preferably vary in width depending on the length of the rack section carried thereby. 110 Each supporting arm 81 is pivotally mounted on the pivot rod 52 like the arms 50 hereinbefore described, and like each of said last mentioned arms is spring pressed downwardly by a spring 59, is limited in its downward movement by a screw stop 61, and is limited in its upward movement by the cross 115 rod 55. The downward pressure of each spring 59 on the associated rack section tends to maintain such rack section in engagement with the feed pinion 28, or in a position to engage the same during the travel of the carriage. However, each of 120 said sections may be moved up from its normal position independently of the others 125 against the force of its spring to disengage such section from the feed pinion. If the rack 47 is ineffective at this time, the carriage will be permitted to advance with a tabulating movement under the power of 130

its spring drum until the first tooth of the next rack section to the right reaches the feed pinion and arrests the carriage. These rack sections differ in detail and in the number of teeth carried thereby, depending on the character of tabulating work to be produced, or in the main on the number of characters to be written in each columnar field.

10 In the present instance the tabulating rack is specially designed with a view to writing in five columns of given character and spacing, as indicated at 82, 83, 84, 85 and 86 on the blank 24, shown in Fig. 2. Obviously, however, the design of the tabulator rack sections may be varied to accord with the particular character of the work to be produced and the blank employed. It is intended to write either two or three characters 15 in the first column 82, an indefinite number of characters up to, say, seventeen in the second column 83, two or three characters in the third column 84, two characters by a single printing stroke of a logotype type bar in the fourth column 85, and a single character in the last or fifth column 86.

15 The rack 47 is first locked in the released position shown in Figure 8, as hereinbefore described, before tabulating work is to be produced.

20 Referring now more particularly to Figures 9 to 15, it will be explained in detail how each of these aligned independently movable rack sections is constructed and controlled to accomplish the results referred to. The feed pinion 28 thus far described, except for its length, is an ordinary fifteen tooth pinion and when the carriage is in position to begin a line of writing, is received 25 in an unobstructed space 87 in the rack section 75 to the left of the tooth 88, as shown in Figures 9 and 14. This enables the tooth 88 of said rack section to normally engage a tooth in the position of the tooth *a* (Figure 9) of the feed pinion, and hold the carriage against advance movement. However, 30 it will be seen that the untoothed portion or space 87 enables the carriage to be shifted to the right from its normal position a limited distance independently of the feed pinion, for purposes which will hereinafter appear. An engaging edge or contact 89 will, in the movement of the carriage to the right from the Fig. 14 position, engage and kick back the feed pinion as indicated in Fig. 35 15, for purposes which will be presently described. The only "tooth" on this rack section, other than the tooth 88, is formed by the right-hand wall 90 of the interdental space 91, said wall in effect forming a "tooth" for controlling the rack. The lower end of this wall is preferably slightly rounded at 92 to prevent a tooth (see *b* in Fig. 10) of the feed pinion obstructing the movement of the carriage when a tabulating

movement from this section to the next is effected.

There being two teeth 88 and 90 on the first rack section this ordinarily enables the operator to write one or two characters in the first or date column 82, though as many as three may be written, as will presently appear. Let it be assumed that the abbreviation of the month of, say, "July" has been written at the head of the first column 82 75 on the blank 24, and that the operator desires to write beneath the month a single digit indicating the day of the month, as shown in the first line on the blank in Figure 2. This may be done by first striking the space key and then the "2" key or vice versa, and the last key operated will result in the feed pinion 28 moving from the Figure 9 to the Figure 10 position. If on the other hand a day of the month contains two digits as shown in the second line on the blank, these are successively written, leaving the feed pinion in the Figure 10 position. In thus turning the feed pinion, the tooth *c* thereof will have engaged the lower edge of an untoothed filled-in portion 93 of the section 75, automatically lifting said section against the force of its spring 59, as indicated in Fig. 10. This releases rack section 75 from the pinion and releases the carriage from control of said section, so that the carriage may move to the left until arrested by the next section 76 co-acting with the feed pinion. The untoothed or filled-in portion 93 preferably terminates at its lower edge 94 100 in a line substantially coincident with the lower end or crown of the tooth 88. The length of the edge 94 is dependent on the length that the carriage is to travel when freed from the particular section thus disengaged from the pinion. The distance from the last character in the first column 82 to the first character in the second column 83 is, in the present instance, two letter spaces, therefore the length of the edge 94 is such 105 as to afford a two-letter space movement of the carriage before it is arrested. Figure 10 shows the parts as they appear just after the section 75 has been automatically lifted and released from control of the feed pinion, but before the carriage thus released has started to advance. From this figure, it will be seen that at this time the tooth *c* stands interposed in the path of the first tooth 95 of the second rack section 76, 110 ready to arrest the carriage after it has been moved two letter spaces to the left. The forward corner of the tooth 95 is preferably rounded slightly at 96 to prevent the carriage from being arrested by the tooth 95 115 catching on the pinion tooth *d*. Should there be a contact between these teeth, the rack section 76 will be cammed up slightly to permit the tooth 95 to slide over and clear the pinion tooth *d*, and engage the 120

tooth *c* thereof as intended. A cut-out 97 in the right-hand end of the section 75, and corresponding cut-outs 97^a and 97^b in each of the sections 77 and 78 respectively, is 5 preferably provided to enable each of these sections to be returned by its spring 59 to its lower normal position at the earliest possible moment after passing out of control of the feed pinion 28 and to the left 10 thereof, as will be clearly understood from a consideration of Fig. 13.

After the date is filled in as explained, the carriage will be arrested by the tooth 95 15 engaging the tooth *c* of the feed pinon; after having automatically skipped from the first to the second columnar field to begin writing within the second or "Place called" column.

Inasmuch as the amount of writing in this 20 column 83 is variable, a release of the carriage to skip from this columnar position to the next is not automatically effected like the other sections, but is key controlled, preferably by the space key of the machine, as will now appear. The rack section 76 has in addition to the rounded tooth 95 uniformly 25 spaced teeth 98 throughout the length thereof, to provide for writing within the second column 83 for an extreme distance corresponding to the length of this rack section.

30 By referring to Figures 1, 6 and 14, it will be seen that a flange 99 extends rearwardly from the rear face of the rack section 76 and has a foot-piece 100 by which it is secured to said section by the headed screws 80 that secure 35 the section to its supporting arm. The right-hand end portion of the flange 99 inclines upwardly to the right to form a cam 101 for purposes to be presently explained. Projecting up through a recess in the top 40 plate, and through an opening in the bracket arm 102 of the escapement wheel, is a release rod 103, the upper end of which terminates beneath the path of travel of the flange 99 as the latter moves with the carriage. The lower end of the rod 103 is pivoted at 104 to a crank arm 105 on the rock shaft 40 to which the space key is connected.

Whenever the carriage is in a certain zone 50 or in a position to write within the second column, the flange 99 will be positioned above the releasing rod 103. An actuation of the space key at this time will move the rod 103 upwardly and the latter co-acting with the flange 99 will elevate the section 55 76, as shown in dotted lines in Fig. 11. This disengages the teeth of said section from the freed pinion and frees the carriage in order that it may move to the next columnar field. The carriage is arrested in such next 60 columnar field by the first tooth 106 of the rack section 77 engaging a tooth of the feed pinion positioned exactly as the tooth *c* is in Fig. 10, as indicated by the dot and dash line *a*. As the writing within the second or 65 "Place called" column may vary, depending

on the length of the name or the abbreviation of the name of the place called, or to which a telegram is sent, as "N Y" or "Duluth" in the example shown, the extent of letter feed within this column will vary. 70 However, the length of the rack section 76 is sufficient to take care of the longest name. An actuation of the space key after the name or abbreviation has been written in this column, will in every instance release the rack 75 section 76. However, an actuation of the space key before this column is reached or after it is passed has no effect on the section 76; the flange 99 at such times being out of the range of movement of the release rod 80 103. If the operator should for any reason maintain pressure on the space key after the flange 99 has passed the rod 103 and during the return movement of the carriage, this ordinarily might result in injury to the machine by the right-hand end of the flange 99 colliding with the projecting rod 103. This would be especially true when power driven means are employed to return the carriage. 85 However the provision of the cam 101 merely results, in the circumstances, in camming down the rod 103 and elevating the space key against the pressure of the operator's finger, and no damage to the parts could result. 90

It has been explained that this independent elevation of the rack section 76 by an operation of the space key after completing the writing of the name of the place called, brings about an arrest of the carriage 95 through the tooth 106 of the next section 77 100 with a tooth of the feed pinion positioned on the line *a* to begin writing in the third or "Amount" column 84. Ordinarily two digits are to be written in this column before the section 77 is automatically lifted to permit the carriage to skip to the next columnar field. Therefore, one additional tooth 105 110 115 120 125 130 107 is provided on this rack before the closed or filled-in untoothed portion 108 of this section is reached. When two digits, as indicated in the first line of the partly filled-in blank are to be written in this space, the appropriate printing keys are actuated in the usual manner and on completing the stroke of the second key the section 77 will be automatically lifted as shown in Fig. 12 to free the carriage to skip to the next columnar field. While ordinarily but two digits in the units and tens positions are written in the third or "Amount" column, it sometimes becomes necessary to write three digits in the hundreds, tens and units positions, as indicated in the second line of the blank. This may be readily accomplished by the operator holding down the space key in jumping the carriage from the second to the third column until after the first or highest digit ("1" in the example shown) is written in the hundreds position. This is

effective to hold the carriage in position to write said highest digits in the proper place, since the let-off of the carriage to bring it to the second or tens place does not occur until 5 the return movement of the space key. In this manner three, as well as two, characters may be written when desired in the third column before the carriage is automatically spaced to the next columnar field. The object of providing a flat face on the holding dog 29 of the escapement, as previously explained, is to aid in effectively carrying out the above result of writing within the proper denominational positions either before 10 or after releasing the space key, and for effectively holding the carriage against accidental skipping or advancing during the operation of the space key.

An arrest of the carriage for writing in 20 the next or "Tax" column is effected by the front face 109 of section 78 striking a tooth of the pinion positioned on the line α , which it will be observed is the same point at which the carriage is freed from control of the 25 preceding rack section. This is likewise true of the automatically lifted rack sections 75, 77 and 78, as will be readily understood by observing the line α in Figures 10, 12 and 13. The construction in the present instance is 30 such that a single printing operation is permitted when writing within the fourth or "Tax" column. The amount of the tax which is either five or ten cents is therefore carried on two special, independently operated, logotype type bars, one carrying the type to print "05" and the other "10". A single operation of either of these type bars is effective to print the corresponding characters and automatically elevate the rack 35 section 78 by a tooth of the pinion co-acting with the untoothed filled-in portion 110 of said sections, as shown in Fig. 13. This will result in the carriage moving two letter 40 spaces, in the present instance, to the next or last columnar field where the carriage is arrested by the first tooth 111 of the last rack section 79 co-acting with a tooth of the feed pinion. There is no untoothed or 45 filled-in portion on the rack section 79, the tooth 111 and the remaining teeth 112 thereof being uniformly spaced apart. The exact 50 number of teeth employed in this section 79 is immaterial since usually a single code character is to be written therein before the 55 line lock, if one be employed, is actuated at the end of the line, or the line stops co-act to arrest further movement of the carriage. It is also immaterial whether or not this last 60 rack section 79 is pivoted, since there is no necessity of releasing it.

In the construction thus far described, the feed pinion 28, except for its length, is shown as the usual fifteen-tooth pinion. In such a construction it may be found desirable in addition to rounding off the corners

of the teeth 92 and 96 as previously pointed out, to round off the forward advancing corners of the first tooth on each of the sections 77, 78 and 79 as indicated at 113, 114, and 115 respectively. This is in order to 70 prevent these teeth from catching on a tooth or pinion located as the tooth d is in Fig. 10 when the carriage skips from one columnar position to the next. Should these teeth collide the rack section carrying the rounded 75 tooth will be slightly elevated to ride over the co-acting tooth of the feed pinion and enable the carriage to be properly arrested by co-acting always with a tooth of the pinion disposed in the position indicated by the line α passing through Figures 9 to 13. As previously pointed out, such line indicates the position of the tooth of the feed pinion in each instance when one rack section is automatically released from the 80 pinion and the next succeeding rack section co-acts with the same tooth to arrest the carriage. While this rounding off of the teeth in the manner indicated is not necessary in practice, even when a fifteen-tooth pinion is 85 employed, I prefer to round the teeth in the manner indicated. In some instances, this rounding of the teeth of the rack sections is entirely unnecessary because there is no 90 chance of the rack sections colliding with the wrong tooth of the feed pinion. This is 95 illustrated in Figure 16 wherein an ordinary (except for its length) twelve-tooth feed pinion 28^a is shown. From this figure, it will be seen that a sharp-cornered tooth 95^a 100 on the section 76 will clear the tooth 116 of the pinion, and will be properly arrested by the tooth 117 thereof. So it is with the teeth of all the remaining rack sections when a twelve-tooth pinion is employed.

It is sometimes desirable to write three characters as well as two within the first column for the purpose of writing an abbreviation of the month, as "Jul" for example. This does not often occur; a single month 110 or at most two months being indicated on each bill. In order that the abbreviation of a month or several such abbreviations may be written on each bill, I provide the following construction:

In the standard Remington machines, margin stops coact to limit the return movement of the carriage, and when the latter is in proper position to begin a line of writing such stops are in contact and the carriage 120 can be moved no further to the right so long as said stops remains one in the path of the other. Moreover, in such constructions, even if the carriage could be shoved back one space from its normal starting point, it 125 would be held in such position by the usual backing ratchet and would not again drop forward to its original position when backward pressure on the carriage is released. If on the other hand there should be a relative 130

adjustment effected between the backing pawl and ratchet this might suffice for a forward drop of the carriage for only a fraction of a letter space. This amount, however, would be insufficient for the purpose of the present invention which requires at least a full letter space forward drop of the carriage from the margin stop. In the present instance I have modified the arrangement 10 of the parts and so constructed the machine that there is a forward drop of the carriage in the direction of its feed a full letter space distance after the carriage stops co-act to arrest the return movement of the carriage. 15 Therefore, the normal beginning of the line is one letter space to the left of where the stops co-act, for purposes which will now be explained.

What has just been said will be better understood from a consideration of Figures 2 to 5, inclusive and Figures 14 and 15. It will be seen that a margin stop 118 carried by and adjustable along the front guide rail of the carriage co-operates with a suitable 25 stop 119 on the frame of the machine to limit the movement of the carriage to the right, and that a stop 118 coacting with the stop 119 limits the range of movement of the carriage in the opposite direction. As indicated above, at the beginning of a line, the stops 118 and 119 are spaced apart in the present instance, a letter space distance, as shown in Figure 2. In this position the carriage pointer co-acts with the indication on 30 the carriage scale, denoting the twenty-ninth point thereon as the beginning of the normal line. The letter space thus provided between the stops is due in the main to the fact that when the carriage is at rest with the parts in 35 the Figures 3 and 14 position, there is a lost motion connection between the carriage and the feed pinion that enables a backward movement of the carriage to be effected independently of the feed pinion and the back- 40 ing ratchet 32 connected therewith. This independent movement of the carriage is permitted by the elimination of all teeth from the rack section 75 to the left of the tooth 45 88 thereon, so that the carriage is capable of moving to the right from the Figures 2 and 14 position without turning the feed pinion, and any desired extent of independent movement might be obtained by such means. So 50 far as this feature of my invention is concerned, the contact 89 might be entirely eliminated without interfering with the movement of the carriage independently of the back spacing ratchet and pawl. Disregarding for the moment the contact 89, and consider- 55 ing it as omitted from the rack section 75, it will be seen that a movement of the carriage to the right from the starting point could be effected for an indefinite distance or until the carriage is arrested by the margin stops. During such movement the feed 60

pinion stands at rest, and when the carriage is released from the backward pressure the spring drum will move it to the left until the tooth 88 strikes the feed pinion and the carriage will be arrested in its initial position 70 from which it was moved to the right. This principle of construction may be availed of for other purposes than that specifically referred to above. However, for a distinct purpose to be hereinafter brought out, I 75 deem it advisable in the present construction to use the contact 89, and when it is used there is only a limited extent of independent movement of the carriage before the pinion, and ratchet wheel 32 connected therewith, is 80 kicked back by the contact 89. Therefore, there is a displacement of said ratchet wheel in the present instance which must be taken into consideration. Thus, it will be seen that when the carriage is moved back by 85 hand from the Figures 2 and 14 position, the first part of the movement through a fraction of a letter space is the independent movement of the carriage described above. This continues until the contact 89 strikes a 90 tooth of the feed pinion 28 and moves it together with the ratchet wheel 32 backward a fraction of a letter space; the ratchet wheel moving from the Fig. 4 to the Fig. 5 position. This fractional kicking back of the 95 ratchet wheel is to insure the proper engagement or register of the pawl 31 with the proper tooth of the ratchet wheel 32 when the carriage is released from backward pressure and drops forward to the position from 100 which it had been moved, or from the point indicating twenty-nine to the point indicating twenty-eight on the carriage scale. It will be seen that in moving the carriage backward one space, or until the stops 118 105 and 119 co-act, a fraction of such movement is due to the movement of the carriage independently of the feed pinion. During the remaining fraction of the letter space movement the feed pinion is kicked back through 110 the engagement of the contact 89 with the feed pinion. Figure 15 shows a relation of the parts 75 and 28 when the carriage has completed its push back movement. When 115 the carriage is released from backward pressure and drops forward in the direction of its feed, the carriage with the section 75 will first move to the left from the Fig. 15 position by an independent movement. When the tooth 88 reaches the feed pinion 28, the latter together with the ratchet wheel 32 will be turned forward from the Figure 5 to the Figure 4 position, arresting the carriage at the last mentioned position, or when the carriage is at the point indicating twenty- 120 eight on the carriage scale. 125

From what has been said above, it will be apparent that should the operator desire to write the abbreviation of the month on a bill, it is merely necessary to force the carriage 130

8
to the right from the Fig. 2 to the Fig. 3 position, and while the carriage is held in this last mentioned position effect an imprint of the first letter, say "J", of the abbreviation

5 and then release the carriage. The said letter "J" will appear on the paper one letter space to the left of the letters, say "UL" to be subsequently written in the usual manner, and which are indicated in Fig. 2.

10 After the last letter, "L", is written the carriage will be automatically tabulated to the next columnar field as previously described, and the operator may proceed as hereinbefore indicated.

15 While I have described in detail the operation of each of the parts of the construction, a brief general description of the operation of the machine as a whole may not be amiss. The operator places the slip or form 24 in 20 the machine as shown, either to enter the first charge or to enter an additional charge on a slip having entries already included thereon. Usually only a single line is written on the slip at a time and a great many are handled, 25 so that the saving of time in making entries is of the utmost importance.

The slip having been introduced into the machine and positioned to receive a line of writing, the carriage is moved to the right 30 until arrested by the stops 118, 119. This positions the carriage to enter the date in the column 82 which may have a caption showing the month. If not, the abbreviation of the month is entered in the manner hereinbefore described. The day of the month is then entered as previously indicated, and the carriage will be automatically skipped to the second columnar field ready to enter the place called in the next column. After the place called has 35 been entered the operator depresses the space key, causing the carriage to skip to the third columnar field where the entry may be made in the third or "Amount" column as previously described. When the operator writes 40 a character in the units position the carriage will be automatically jumped to the next or fourth column. A single stroke of the key controlling a logotype type bar will write the corresponding amount of the tax in this column, and that will result in automatically 45 skipping the carriage to the final or code column, where ordinarily a single character is written. The line having thus been written on the blank it is rapidly withdrawn and another blank introduced and the operation 50 repeated.

Should the operator desire to use the machine as an ordinary correspondence machine it is simply necessary to shift the finger piece 72 to the Fig. 7 position. This releases 55 the rack 47 and allows it to engage the feed pinion. The operator may then proceed in the usual manner, the carriage being under control of the feed rack 47 and out of con- 60 trol of the tabulator rack. While the rack

sections of the tabulator rack will be automatically lifted and dropped during the travel of the carriage, this is immaterial and will not affect the control of the carriage by the rack 47.

70 While I have shown and described one means by which the carriage may be pushed back at the beginning of a line one letter space distance to provide for writing an additional character in the first columnar field, I am aware that other forms of construction may be used. I wish to be understood as not restricting myself to the form of mechanism shown but to include any suitable mechanism for the purpose stated within the 75 broad purview of my invention as defined in certain of the following claims.

80 The machine embodying my invention has proved highly efficient in practice, enabling an operator to introduce, fill in, and remove a slip with great rapidity.

85 It will be seen, moreover, the ordinary No. 10 or No. 12 Remington machine may be readily converted to embody the features of my invention.

90 What I claim as new and desire to secure by Letters Patent is:—

1. In a typewriting or like machine, the combination of a carriage; and means for controlling the movement of the carriage comprising a feed pinion, a plurality of members independently movable into and out of holding engagement with said pinion, each member having one or more teeth and normally positioned to have a path of movement that will bring it into engagement with said pinion, and means whereby said members are successively and automatically disengaged from said pinion at given points in the travel of the carriage by co-operation 100 with said pinion.

2. In a typewriting or like machine, the combination of a carriage; and means for controlling the movement of the carriage comprising a feed pinion, a plurality of normally aligned members independently movable into and out of alignment and into and out of engagement with said pinion, and means whereby said members are successively and automatically thrown out of alignment at given points in the travel of the carriage.

3. In a typewriting or like machine, the combination of a carriage; and means for controlling the movement of the carriage comprising a feed pinion, a plurality of normally aligned members independently movable into and out of alignment and into and out of engagement with said pinion, and means whereby said members are successively and automatically thrown out of alignment at given points in the travel of the carriage and through the co-operation of said members with said pinion.

4. In a typewriting or like machine, the

- combination of a carriage; and means for controlling the movement of the carriage comprising a feed pinion, a plurality of normally aligned members independently movable into and out of alignment and into and out of engagement with said pinion, said members being spring-pressed to aligned position, and means on each of said members automatically co-operative with said pinion 5 to successively move the individual members against the pressure of their springs and out of alignment and engagement with the pinion as the carriage reaches different given points in its travel.
- 15 5. In a typewriting or like machine, the combination of a carriage; and means for controlling the movement of the carriage comprising a feed pinion, a plurality of members independently movable into and out of engagement with said pinion, and automatically operating means by which the said independent movement of the members is successively effected at given points in the travel of the carriage.
- 20 6. In a typewriting or like machine, the combination of a carriage; and means for controlling the movement of the carriage comprising a feed pinion, a plurality of members of different lengths independently movable into and out of engagement with said pinion and normally in position to engage said pinion, and automatically operating means by which said members are successively disengaged from said pinion at given points in the travel of the carriage.
- 25 7. In a typewriting or like machine, the combination of a carriage; and means for controlling the movement of the carriage comprising a feed pinion, a plurality of rack sections independently movable into and out of engagement with said pinion, a plurality of spring pressed pivoted carriers on which said rack sections are mounted, and automatically operating means controlled by the position of the carriage in its line of travel 40 for controlling successively such independent movement of said rack sections.
- 45 8. In a typewriting or like machine, the combination of a carriage; and means for controlling the movement of the carriage comprising a feed pinion, a plurality of rack sections which vary in length and are independently movable into and out of engagement with said pinion, and automatically operating means controlled by the position of the carriage in its line of travel 45 for controlling successively such independent movement of said rack sections.
- 50 9. In a typewriting or like machine, the combination of a carriage, automatically operating means for causing the carriage to skip from the first to the second columnar position, means which enable the carriage to be moved from its normal position at the beginning of a line beyond or back of such po-
- sition at least a letter space distance by a mere backward pressure exerted on the carriage in order that at least one additional character may be written in the first column, and means for arresting the said backward movement of the carriage after it has been thus back spaced the requisite distance.
- 55 10. In a typewriting or like machine, the combination of a carriage; and means for controlling the movement of the carriage 70 comprising a feed pinion, a plurality of rack sections independently movable into and out of engagement with said pinion, key controlled means operative only at a given portion of the travel of the carriage to disengage one of said rack sections from the pinion, and automatically operating means for successively disengaging other of said rack sections from the pinion determined by the position of the carriage in its line of travel.
- 60 11. In a typewriting or like machine, the combination of a carriage; and means for controlling the movement of the carriage comprising a feed pinion, and a plurality 75 of co-operative rack sections, one of said sections having one or more teeth at the advancing end portion thereof and having a filled untoothed portion extending substantially to crowns of the rack teeth and from the last of said teeth substantially to the other end of the rack section.
- 65 12. In a typewriting or like machine, the combination of a carriage; and means for controlling the movement of the carriage comprising a feed pinion, and a plurality 80 of co-operative rack sections movable independently into and out of engagement with said pinion and each having one or more teeth at the advancing end portion thereof and having a filled untoothed portion extending substantially to crowns of the teeth thereon and from the last of said teeth substantially to the other end of the rack section, whereby as the filled portion of each rack section reaches the pinion such section 85 will be automatically shifted out of engagement with the feed pinion and the carriage permitted to skip to the next columnar field.
- 70 13. In a typewriting or like machine, the combination of a carriage, a feed pinion, an escapement wheel, intermediate pawl and ratchet mechanism between said escapement wheel and pinion, and means carried by the carriage and cooperative with said feed pinion only at the extreme return movement of the carriage to engage said pinion and assure its disposal in the registering position when the carriage starts to feed forward.
- 75 14. In a typewriting or like machine, the combination of a carriage, a feed pinion, an 115 escapement wheel, intermediate pawl and ratchet mechanism between said escapement wheel and pinion, a rack engageable with said pinion but out of intermeshing engagement therewith when the carriage is re-
- 80 120 125 130

turned to the normal beginning of a line, and means carried by the carriage and co-operative with said feed pinion only at the extreme return movement of the carriage to engage said pinion and assure its disposal in the registering position when the carriage starts to feed forward.

15. In a typewriting or like machine, the combination of a carriage, a feed pinion, and a tabulating rack co-operative with said pinion, said tabulating rack comprising a plurality of sections individually movable into and out of co-operative relation with said feed pinion, and automatically operating means co-operating with said rack sections to move them successively out of co-operative relation with said pinion, whereby when one rack section is shifted out of co-operative relation with the feed pinion the carriage will move until arrested by the next adjacent rack section which remains in effective position.

16. In a typewriting or like machine, the combination of a carriage, a feed pinion, and a tabulating rack co-operative with said pinion, said tabulating rack comprising a plurality of sections individually movable into and out of co-operative relation with said feed pinion, each of certain of said rack sections having an untoothed filled-in portion which co-acts with the feed pinion to automatically shift that individual rack section out of co-operative relation with the feed pinion and enable the carriage to move until arrested by the next adjacent rack section.

17. In a typewriting or like machine, the combination of a carriage, a feed pinion, and a tabulating rack co-operative with said pinion, said tabulating rack comprising a plurality of sections individually movable into and out of co-operative relation with said feed pinion, each of certain of said rack sections having an untoothed filled-in portion which co-acts with the feed pinion to automatically shift that individual rack section out of co-operative relation with the feed pinion and enable the carriage to move until arrested by the next adjacent rack section, the length of each untoothed or filled-in portion corresponding substantially to the length of tabulating movement effected by the section carrying it, whereby each filled-in portion may ride on the feed pinion during the tabulating movement of the carriage and be held out of engagement with the pinion.

18. In a typewriting or like machine, the combination of a carriage, a feed pinion, a feed rack having all feed teeth omitted therefrom at a point to the left of where it co-acts with the feed pinion when the carriage is in position to begin a normal line of writing, whereby the pinion remains at rest during a backward movement of the carriage

beyond its position to begin a normal line of writing, and means for arresting the carriage after a predetermined definite extent of such backward movement of the carriage has been effected.

19. In a typewriting or like machine, the combination of a carriage, a feed pinion, a feed rack member having all feed teeth omitted therefrom at a point to the left of where it co-acts with the feed pinion when the carriage is in position to begin the normal line of writing, whereby the pinion remains at rest during a backward movement of the carriage beyond its position to begin a normal line of writing, means for arresting the carriage after a predetermined definite extent of such backward movement of the carriage has been effected, and automatically operating means for moving said rack member out of co-operative relation with said pinion at a given point in the travel of the carriage.

20. In a typewriting or like machine, the combination of a carriage, a feed pinion, a tabulator rack comprising a plurality of rack sections of different lengths and each having one or more teeth depending on the number of step-by-step letter space movements of the carriage to be effected with the aid thereof, said sections being mounted for individual movement into and out of co-operative relation with said feed pinion, and automatically operating means for successively moving said sections out of co-operative relation with the pinion at given points in the travel of the carriage.

21. In a typewriting or like machine, the combination of a carriage, a feed pinion, a tabulator rack comprising a plurality of rack sections of different lengths and each having one or more teeth depending on the number of step-by-step letter space movements of the carriage to be effected with the aid thereof, said sections being mounted for individual movement into and out of co-operative relation with said feed pinion, and automatically operating means for successively moving said sections out of co-operative relation with the pinion at given points in the travel of the carriage, the said automatically operating means comprising a filled-in portion on each rack section to the right of the teeth thereof and with which the feed pinion co-acts to disengage such rack section from the pinion.

22. In a typewriting or like machine, the combination of a carriage, a feed pinion, a tabulator rack comprising a plurality of rack sections of different lengths and each having one or more teeth depending on the number of step-by-step letter space movements of the carriage to be effected with the aid thereof, said sections being mounted for individual movement into and out of co-operative relation with said feed pinion, auto-

matically operating means for successively moving said sections out of co-operative relation with the pinion at given points in the travel of the carriage, the tabulator rack 5 having an additional rack section with teeth throughout the entire extent thereof, and key controlled means effective only when the carriage is within a certain zone to disengage the last mentioned rack section from 10 the feed pinion.

23. In a typewriting or like machine, the combination of a carriage, a feed pinion, a tabulator rack having means co-operative with the feed pinion to automatically lift 15 the rack and free the carriage for tabulating movement and to arrest the carriage after such tabulating movement has been completed, the construction and arrangement of the parts being such that only a single 20 tooth of the feed pinion co-acts at a time with said rack to automatically free the carriage for tabulating movement and also for effecting an arrest of the carriage after such tabulating movement has been completed, whereby if desired the construction 25 can be arranged to have the carriage skip over but one letter space in a tabulating movement.

24. In a typewriting or like machine, the combination of a carriage, a feed pinion, and a tabulator rack having means co-operative with the feed pinion to automatically lift the rack and free the carriage for tabulating movement and to arrest the carriage 30 after such tabulating movement has been completed, the construction and arrangement of the parts being such that only a single tooth of the feed pinion co-acts at a time with said rack to automatically free the carriage for tabulating movement and also for effecting an arrest of the carriage after such tabulating movement has been completed, such a single tooth of the feed pinion always being in a given invariable position when the release and arrest of the carriage is effected.

25. In a typewriting or like machine, the combination of a carriage, stop means for determining the beginning of a line, a feed 50 pinion, a rack member adapted to mesh with said feed pinion, means which at the normal beginning of a line will permit the carriage to be moved back by merely exerting a backward pressure thereon, and means operative 55 only when the carriage is moved back from its normal beginning-of-the-line position to automatically kick back the feed pinion.

26. In a typewriting or like machine, the combination of a carriage, stop means for determining the beginning of a line, a feed pinion, a feed rack having teeth omitted therefrom at a point to the left of where it co-acts with the feed pinion when the carriage 60 is in position to begin a normal line of writing, whereby the pinion remains at

rest during a backward movement of the carriage beyond its position to begin a normal line of writing, and means operative only when the carriage is being thus moved backward for automatically kicking back 70 the feed pinion a fraction of the distance required for a full letter space movement of the carriage.

27. In a typewriting or like machine, the combination of a carriage, stop means for 75 determining the beginning of a line, escape- 80 ment mechanism therefor including a feed pinion, and means which enable the carriage to be moved from its position to begin a normal line of writing back or beyond such position at least one letter space by mere 85 backward pressure exerted against the carriage and which enables the carriage to drop forward the distance it was moved back when backward pressure is released from 90 the carriage, and means operative only when the carriage is being thus moved backward for automatically kicking back the feed pinion a fraction of the distance required for a full letter space movement of the carriage.

28. In a typewriting or like machine, the combination of a carriage, a tabulator rack, a separate and distinct feed rack, and means 95 that enable the carriage to be maintained indefinitely under control of either the tabulator or the feed rack as may be desired, said means including means for independently shifting the feed rack into or out of use.

29. In a typewriting or like machine, the combination of a carriage, a tabulator rack, a separate and distinct feed rack, and means for independently holding the feed rack out of effective position, whereby the carriage 105 may be controlled by said tabulator rack.

30. In a typewriting or like machine, the combination of a carriage, a feed pinion therefor, a feed rack that meshes with said pinion, a separate and distinct tabulator 110 rack co-operative with said pinion, and means that enable either of said racks to be effective to control the carriage indefinitely.

31. In a typewriting or like machine, the combination of a carriage, a feed pinion therefor, a feed rack that meshes with said pinion, a separate and distinct tabulator rack co-operative with said pinion, and means for independently holding the feed 115 rack disengaged indefinitely from said feed pinion, whereby the tabulator rack controls 120 the travel of the carriage.

32. In a typewriting or like machine, the combination of a carriage; means for controlling the movement of the carriage comprising a feed pinion, a plurality of members individually movable into and out of co-operative relation with said pinion, a feed rack also co-operative with said pinion, means for controlling the individual move- 125 130

ment of said members out of co-operative relation with said pinion; and means for holding the feed rack indefinitely out of co-operation with the feed pinion.

33. In a typewriting or like machine, the combination of a carriage; a feed pinion; a tabulator rack comprising a plurality of rack sections individually movable into and out of co-operative relation with said pinion; automatically operating means for successively moving said sections out of co-operation with said pinion at different points in the travel of the carriage; a continuous feed rack co-operative with said feed pinion; and means operable at will for moving said feed rack to and holding it indefinitely in ineffective position so that the carriage will be controlled by said tabulator rack.

34. In a typewriting or like machine, the combination of a carriage, a feed pinion, a tabulator rack co-operative with said pinion, a continuous feed rack likewise co-operative with the feed pinion, a carriage release key for shifting said feed rack out of co-operation with the pinion, and a shifting and locking key co-operative with said locking key to shift the latter and lock it in its actuated position and thus maintain indefinitely the feed rack out of co-operative relation with said pinion.

35. In a typewriting or like machine, the combination of a carriage; stop means for determining the beginning of a line, a feed pinion, a rack member adapted to mesh with said feed pinion, and means which at the normal beginning of a line will permit the carriage to be moved back by exerting only sufficient backward pressure thereon to overcome the weight of the carriage and the force of the carriage spring and while said stop means are maintained in the normal effective condition.

36. In a typewriting or like machine, the combination of a carriage; a feed pinion; an escapement wheel; pawl and ratchet mechanism between said pinion and wheel; stop means for arresting the carriage and determining the normal beginning of a line comprising a stop on the carriage, a coacting stop on the frame of the machine, said stops being fixed against displacement on the parts which carry them in the cooperation of the stops for limiting the return movement of the carriage; means which engage said pinion to turn it during the forward letter space movement of the carriage; and means

separate and distinct from said stops which enable the carriage by a mere backward pressure thereon to be shoved back a predetermined definite extent beyond the normal beginning of the line position and then arrested, a release of pressure on the carriage after said arrest bringing about a separation of said stops a distance equal to the amount the carriage was moved back.

37. In a typewriting or like machine, the combination of a carriage, margin stops for limiting the return movement of the carriage, and automatically operating means which enable the carriage to drop forward at least one letter space after it has been arrested by said stops and from the point of contact between the stops, said automatically operating means being separate and distinct from said margin stops.

38. In a typewriting or like machine, the combination of a carriage, margin stops for limiting the return movement of the carriage, said stops being fixed on the parts that carry them in cooperating to arrest the carriage, and automatically operating means which enable the carriage to drop forward at least one letter space after it has been arrested by said stops and to permit the carriage to be shoved back until arrested by the stops and immediately drop forward again at least a letter space distance when backward pressure is released on the carriage.

39. In a typewriting or like machine, the combination of a carriage; stop means for determining the beginning of a line comprising a stop on the carriage, a coacting stop on the frame of the machine, said stops being fixed against displacement on the parts which carry them in the cooperation of the stops for limiting the return movement of the carriage; and escapement mechanism therefor including means which enable the carriage to be moved from its position to begin a normal line of writing back or beyond such position at least one letter space by mere backward pressure exerted against the carriage and which enable the carriage to drop forward the distance it was moved back when backward pressure is released from the carriage.

Signed at the borough of Manhattan, city of New York, in the county of New York and State of New York, this 3rd day of July A. D. 1924.

EDWIN E. BARNEY.
